UNITED STATES PATENT OFFICE.

ROBERT WILLOUGHBY Vining, of London, England.

AUTOMATIC APPARATUS FOR TAKING PHOTOGRAPHS.

SPECIFICATION forming part of Letters Patent No. 606,318, dated June 28, 1898.

Application filed March 28, 1898. Serial No. 675,494. (No model.)

To all whom it may concern:

Be it known that I, ROBERT WILLOUGHBY Vining, residing at Ealing, London, in the county of Middlesex, England, have invented 5 an Improvement in Coin-Freed Automatic Machines for the Taking and Delivery of Photographic Impressions, (for which I have made application for Letters Patent in Great Britain under No. 10,906, dated May 1, 1897,) 10 of which the following is a specification.

My invention relates to machines for automatically taking photographs and delivering the same in exchange for a coin or coins or tokens, and has for its object the provision 15 of means for carrying out the cycle of operations so that the necessary adjustment of exposure can be made according to the variations of the light, and the development of the photograph-image can be automatically regulated according to the temperature, these 20 being the two varying factors which affect the final result.

In order that my invention may be the better understood, I will now proceed to describe 25 the same in reference to the accompanying drawings, reference being had to the letters marked thereon.

Like letters refer to like parts in the various figures.

30 Figure 1 is a back elevation of my machine. Fig. 2 is a front elevation of the same, the casing in each case being removed to show the mechanism. Fig. 3 is a plan of the same. Fig. 4 is a sectional plan showing the various 35 baths and plate-carriers. Fig. 5 is a detail view of the plate-carriers and operative mechanism. Fig. 6 is a developed view of the zig-zag path controlling the plate-carriers. Fig. 7 is a detail view of the operative mechanism 40 for controlling the lower carrier. Fig. 8 is a view of the two carriers, one above the other, showing the relative position when the photographic plate is to be delivered from the upper to the lower carrier. Fig. 9 is a side 45 elevation of the machine, showing the winding-up gear. Figs. 10 and 11 show in two positions the thermostatic regulator for controlling the speed of the clockwork according to the surrounding temperature, and Fig. 12 is a part-sectional view of the cylinder containing 50 the zigzag path.

To carry my invention into effect, I arrange

a pile of superimposed sensitized plates A on the upper part of the machine, (shown in Figs. 1, 2, and 9,) and I provide mechanism at the 55 lower part of the pile, so arranged that on each operation of the machine a sensitive element or plate is fed from the bottom of the pile into position at the back of the lens B, Fig. 9, of the camera C, Figs. 2, 3, and 9. 60 This mechanism consists of a horizontal screw D, Figs. 3 and 9, engaging with a sliding catch E, Figs. 3 and 9, which is so arranged that it will engage the lowermost plate and push it from beneath the pile through a slot 65 in the side of the container into the hopper F, Figs. 2, 3, and 9, which is adapted to deliver the said plate in the proper focal plane at the back of the camera. The screw D, Figs. 3 and 9, carries a pinion d, Figs. 1, 3, 70 and 9, with which a rack d², Figs. 1, 3, and 9, engages, the means for the operation of the said rack being hereinafter described.

I arrange a clockwork mechanism G, Fig. 1, in the upper part of the device, which is 75 driven in the ordinary way by the weight g, Figs. 1, 3, and 9, and is provided with a controlling time-disk H, Figs. 1, 2, 3, 5, and 9, with which engages a detent J, Figs. 2, 3, and 5, operated by the coin-lever k, Figs. 2 and 3. 80

The control-disk H, Figs. 1, 2, 3, 5, and 9, carries a projection h, Figs. 2, 3, 5, and 9, which is adapted to coact with the operating mechanism h², Figs. 2, 3, and 9, of the shutter K', Figs. 2 and 9, pivoted on an axle K, 85 Figs. 3 and 9, so as to open and close the said shutter, the two positions of the shutter being shown in dotted lines in Fig. 9.

The plate when in the camera rests upon a false bottom L, Fig. 3, placed over a slot in 90 the floor in the apparatus. This false bottom L, Fig. 3, is adapted to slide and is spring-pressed by a spring l, Fig. 3, and has a slot which is of such a size as to allow the plate to drop through the floor when the slots in 95 the false bottom L and the floor coincide. The operation of the false bottom L, Fig. 3, is controlled by a pivoted arm l², Fig. 3, to which it is connected, the end of the arm l², Fig. 3, carrying a projection arranged to engage with a recess l³, Fig. 5, on the controlling-disk H, Figs. 1, 2, 3, 5, and 9, when the said disk is in such a position as to allow the engagement of the recess l³, Fig. 5, and the 100

end of the lever l^2 , Fig. 3, which are made of such a form as to allow the disk to force the lever back out of the recess against the spring-pressure of the spring l , Fig. 3, as the rotation of the disk proceeds. The plate drops from the camera into a developing-carrier M , Figs. 1, 4, and 5, which is carried upon an arm m , Figs. 1, 4, and 5, mounted rigidly upon a post m^2 , Figs. 1, 4, and 5, slidingly held in the supporting-cylinder N , Figs. 1, 4, and 5. The post m^2 carries a piston having a projection m^3 , Fig. 12, which is adapted to engage with slots m^4 , Figs. 6 and 12, arranged in the interior of the cylinder, the vertical slots being connected by diagonal slots m^5 , Figs. 6 and 12, controlled by spring-switches m^6 , Figs. 6 and 12. The top of the post m^2 is attached by a swivel O , Figs. 1 and 5, to a strap or cord o , Figs. 1, 2, 3, and 5, which in turn is fastened to a quadrant o' , Figs. 1, 2, 3, 5, and 9, by a lever o^2 , Figs. 1, 2, 3, 5, and 9. The small arm o^3 , Fig. 5, which is rigidly attached to the lever o^2 , is engaged by the projection on the time-disk, so as to lift the post with its carriers. Around the post m^2 I arrange the developing-tank P , Fig. 4, and on a lower level the fixing-tank P' , Figs. 1 and 4, and washing-tank P'' , Figs. 1 and 4, and delivery-chute P^3 , Figs. 1 and 4.

Above the developing-carrier M , I loosely mount the sleeve Q , Figs. 1, 5, and 7, upon the post m^2 . The said sleeve Q carries an arm Q' , Figs. 4, 5, and 7, to which is depended the fixing-carrier Q^2 , Figs. 1, 4, and 5. Each of the carriers M and Q^2 is provided with a sprung-pressed projection or catch q , Figs. 1 and 5, which in its normal position prevents the plate from falling through the carrier. The controlling-disk H gears with a pinion q' , Figs. 3 and 5, which operates with a mutilated spur-wheel q^2 , Figs. 3 and 5, which engages at right angles with a similar mutilated spur-wheel q^3 , Figs. 3 and 5, attached to the sleeve Q . The object of this double arrangement of carrier is to allow the use of one dipping device for developing and another dipping device for fixing and washing in order to prevent the contamination of the developing-bath with the fixing solution, which would be the case if the same carrier or dipper were used for all three baths.

To allow for variations of light, I fit the lens with the usual diaphragm or stop b , Fig. 9, to which is connected an adjusting-gear b^2 , Figs. 3 and 9, capable of being operated from the exterior of the casing containing the machine, and I arrange a scale having suitable directions, upon which works a pointer connected with the diaphragm-adjusting mechanism, so that the illumination of the image on the sensitive surface can be varied by the size of the aperture of the lens being altered by the person who desires to be photographed.

As the rate of development of the photographic image depends very largely on the temperature of the developing solution I provide means to correct the differences of

development due to variations of temperature. To effect this, I arrange the clockwork mechanism G with a controlling device consisting of a flier R , Figs. 1, 10, and 11, having wings adjustable on their axes so as to vary the resistance of the flier to rotation through the air. The adjustment of these wings is effected by means of a sliding sleeve r , Figs. 10 and 11, connected to an eccentric-pin on the wings by a connecting-rod r' , Figs. 10 and 11. The movement of the sleeve r is controlled by a wedge r^2 , Figs. 10 and 11, connected by an adjusting-screw r^3 , Figs. 10 and 11, through a lever r^4 , Figs. 10 and 11, to one end of a coil of tubing r^5 , Figs. 1, 3, 10, and 11, containing a volatile fluid, the other end of the coil being rigidly supported on the frame of the machine, so that the whole device is adapted to act as a thermostatic regulator.

The clockwork mechanism is reinforced at each operation through a device which is operated from the exterior of the machine by the person using it, consisting of a rack S , Figs. 1 and 9, gearing with a pinion s , Figs. 1 and 9, on the main axis of the clockwork mechanism G . This rack is provided with a stem s' , Figs. 1 and 9, adapted to be guided in a guidance s^2 , Fig. 1, arranged on the lower floor of the device. The stem s' , Fig. 9, carries a projection or stop s^3 , Fig. 9, which is adapted to engage with another rack s^4 , Fig. 9, having a stop s^5 , Fig. 9. This rack s^4 is attached to a spiral spring s^6 , Figs. 4 and 9, depended from the upper floor of the machine. The pinion T , Fig. 9, supported on the frame, gears on one side with the rack s^4 and on the other side with a cogged quadrant t , Figs. 1, 2, and 9, to which is attached the lever t' , Figs. 1, 2, 3, and 9, carrying a pulley t^2 , Figs. 1, 2, 3, and 9, on its end. When the lever is pulled, say, from the right to the left, as shown in Fig. 9, the quadrant t revolves the pinion T and pulls down the rack s^4 against the tension of the spiral spring s^6 , the stop s^5 engaging with the stop s^3 in carrying the rack S down with it, so as to revolve the pinion s of clockwork mechanism in order to wind up the weight g .

In order to prevent the partial reinforcement of the clockwork mechanism, I provide a controlled device which is only put out of action at the extreme ends of the stroke of the lever t^2 . This device consists of two ratchet-wheels U and U' , Figs. 1, 2, and 9, which are attached in reversed position to one another to the pinion T . A double-armed pallet u , Fig. 9, is pivoted so as to engage with the two ratchet-wheels U and U' and is arranged to coact with the lever t , so as to only release the ratchet-wheels at either end of the stroke.

In connection with the photographic mechanism I arrange a device V , Figs. 1, 2, 3, and 9, for delivering a mount or frame together with the photograph. This device V contains the mounts or frames, superimposed

one upon another in a pile, and has at its lower part a pair of catches v , Fig. 9, which normally support the superincumbent pile and which when withdrawn from their sphere 5 of action allows the bottom mount or frame to fall out ready for delivery. Another pair of catches v' , Fig. 9, are arranged above the first pair, about the thickness of one mount or frame, and which are adapted to support 10 the rest of the pile during the delivery of the bottom mount or frame, the two pairs of catches v and v' operating alternately in opposite directions.

The catches v are carried by arms v^2 , Figs. 15 1, 2, and 9, pivoted at the upper part upon the mount-container and which are spring-pressed toward one another by the springs v^3 , Figs. 1 and 9. They are operated at their lower part by arms v^4 , Figs. 2 and 9, which 20 are pivoted and attached to levers v^5 , Figs. 2 and 9, the lever v^5 on the right-hand side having an extending arm v^6 , Fig. 9, which is adapted to coact with the pin v^7 , Fig. 9, on the lever t' . The catches v' are attached to 25 the arms v^8 , Figs. 2 and 9, which are also pivoted upon the mount-container, the said arms being adapted at the end beyond the point of pivoting to engage with the arms v^2 of the lower catches, so that the operation of the 30 catches v move the catches v' in the opposite direction.

At the front of the machine I provide a movable list of instructions or information as to the progress of the mechanism and its 35 product simultaneously with its operation, which are set forth on a disk W , Figs. 2 and 9, connected to and moved by the clockwork G , and is designed to afford a source of interest to direct the attention of the person 40 during the taking and delivery of the photograph.

I provide a chain or other equivalent means whereby the proper focal distance can be arrived at by the subject, and I so arrange the 45 chain that it is connected to a flexibly-mounted spring-pressed lever X , Figs. 2 and 3, the upper end of which is provided with a retaining projection x , Fig. 3, which engages with the coin-lever k , Figs. 2 and 3, so that 50 the coin-lever can be released when the proper focal distance is obtained.

The operation of my machine is as follows: The person who desires to be photographed stands in front of the machine, and after having 55 put the necessary coin or coins into the coin-slot takes the focusing-chain and gages the proper distance to place himself from the lens. He then pulls the chain, which is connected to the flexible lever X , Fig. 2, which 60 releases the retaining-catch x , Fig. 2, of the coin-lever k , Fig. 3, the weight of the coin on the end of the coin-lever overbalancing the said lever and withdrawing the detent J , Figs. 2 and 5, from the control-disk H , Figs. 2 and 65 5. This allows the clockwork to be operated by the fall of the weight g , Figs. 1 and 9. The control-disk H in revolving brings the

projection h , Fig. 5, into contact with the shutter-opening gear h^2 , Figs. 2 and 3, and exposes the plate, the period of exposure being regulated by the thermostatic regulator, 70 Figs. 10 and 11. After the shutter is closed the rotation of the disk H brings the recess l^3 , Fig. 5, to coincide with the end of the lever l^2 , Fig. 3, thereby operating the false bottom 75 L , Fig. 3, and allowing the plate to drop through into the upper carrier M , Figs. 1 and 5, this said carrier having been previously raised, with the post m^2 , Figs. 1 and 5, into the upper position by a projection o^4 , Fig. 5, 80 on the disk H , engaging with the lever o^3 , Fig. 5, and raising the quadrant o' , Fig. 5, into its uppermost position. When the projection o^4 is disengaged from the lever o^3 , the post, with its carrier, falls in a vertical line 85 down one of the slots m^4 , Fig. 12, passing by one of the spring-switches m^6 , Fig. 12. As the disk H revolves another projection o^5 , Fig. 5, coacts with the lever o^3 and lifts the post m^2 , Fig. 5, with the carrier. In its ascent the projection m^8 , Fig. 12, travels up one of the diagonal slots m^5 , Fig. 12, into the next vertical slot, and thereby turns the carrier M , Figs. 5 and 4, through a quarter of the circle over the developing-bath P , Fig. 4, and allows it to fall 95 therein. As the disk still continues to revolve another projection o^6 , Fig. 5, engages with the lever o^3 , lifting the post m^2 and revolving it through another quarter of the circle. The normal position of the fixing-carrier Q^2 , Figs. 100 5 and 4, is over the fixing-bath P' , Figs. 1 and 4, being retained in that position by the spring-catch Y , Figs. 1 and 4, mounted on the framing. As the carrier M is moved through the arc last described the spring-pressed 105 catch q , Fig. 8, comes into contact with the carrier Q^2 , Fig. 8, releasing the plate from the upper carrier M , Fig. 8, and allowing it 110 to fall into the lower carrier Q^2 . The lower carrier Q^2 is carried around by the carrier M through the medium of a lever Z , Figs. 5 and 7, pivoted to a flange carried by the post m^2 and spring-pressed by a spring z , Fig. 7, so 115 that the short end of the lever Z is pressed into engagement with a recess z' , Fig. 7, formed in the sleeve Q , carried by the post m^2 . The carrier is now lifted from the fixing-bath P' , Fig. 4, by another projection o^6 , Fig. 5, on the controlling-disk H and is moved 120 around through another arc over the washing-bath P^2 , Fig. 4, into which it drops. It is raised again by projection o^4 , Fig. 5, and in traveling around the catch q , Figs. 5 and 8, of the carrier Q^2 engages with the chute P^3 , Fig. 4, and releases the plate, allowing it to fall 125 down the chute for delivery to the customer. As the post m^2 reaches its upper position the lever Z , Fig. 5, comes into contact with the fixed stop z^2 , Fig. 5, mounted on the under side of the upper floor, which coaction releases the lever Z from the sleeve Q , Fig. 5, and the mutilated spur-wheel q^3 , Fig. 5, engages with the mutilated spur-wheel q^2 , Fig. 5, which returns the lower carrier Q^2 to its 130

normal position against the spring-catch Y, Figs. 1 and 4, leaving the carrier M ready to receive the next plate for developing, &c. After the coin or coins have been delivered 5 down the coin-chute the coin-lever is ready to engage the retaining-slot in the control-disk when the said slot coincides with the lever J, Fig. 5, ready for the next operation.

In order to obtain a mount or frame, the 10 lever ℓ' , Fig. 9, is operated, which causes a frame or mount to be delivered and at the same time reinforces the clockwork mechanism and feeds an unexposed sensitive plate into the camera ready for the next operation.

15 This latter function is carried out by the rack d^2 , Fig. 9, which is attached to or forms a part of the stem s' , Fig. 9, of the rack s , Fig. 9, so that reinforcement of the clockwork and the feeding of a new plate are simultaneously effected. I provide a bell I, Fig. 9, the striker i , Fig. 9, of which is operated by a projection o^8 , Fig. 9, on the back of the control-disk II, so as to indicate to the subject that the exposure is complete.

20 I may arrange a thermostatic regulator controlling a source of heat applied to the developing and other solutions, so that they always keep at a uniform temperature.

Having now described my invention, what 25 I claim, and desire to secure by Letters Patent, is—

1. In an automatic photographic machine, the combination with the tanks adapted to contain the developing and fixing solutions, 30 carrier mechanism for immersing the negative successively in the solutions, suitable motor mechanism for operating said carrier mechanism, and a thermostat for controlling the speed of the motor mechanism.

2. In an automatic photographic machine, the combination with the tanks adapted to contain the developing and fixing solutions, heating means adapted to heat the solutions in the tanks, a thermostat adapted to control 45 the supply of heat to maintain said solutions

at a constantly even temperature, carrier mechanism for immersing the negative in said solutions, substantially as described.

3. In an automatic photographic machine, the combination with the tanks for the developing and fixing solutions carrier mechanism for immersing the negatives successively in said solutions, the motor mechanism for operating said carrier mechanism, the flier for governing the speed of said motor mechanism and having adjustable wings, a thermostat and connections therefrom to the adjustable wings for regulating the speed of the motor according to the temperature, substantially as described. 50 55 60

4. In an automatic photographic apparatus, the combination with the tanks for the developing and fixing solutions arranged upon different levels, of the carrier mechanism comprising an upper carrier adapted to immerse 65 the negative in the upper developing-tank, a lower carrier adapted to immerse the negative in the fixing solution, and means for effecting the transfer of the negative from one carrier to the other, substantially as described. 70

5. In an automatic photographic machine, in combination, a lens and shutter, a holder for the sensitive surfaces, in rear of said lens, tanks for containing the developing and fixing solutions, the carrier mechanism in duplicate for receiving the exposed negative and immersing it in the solutions, the clock mechanism, the timing-disk operated by said clock mechanism, and connections from said timing-disk to the shutter and carrier mechanism, whereby the operation of said parts and the transfer of the negative are effected by the clock mechanism, substantially as described. 75 80

In witness whereof I have hereunto set my hand in presence of two witnesses.

ROBERT WILLOUGHBY VINING.
